DESIGN FOR A DRILLING ATTACHMENT

George A. Terry, Buffalo, N. Y.

Application April 17, 1944, Serial No. 113,281

Term of patent 14 years

(Cl. D54—4)

To all whom it may concern:

Be it known that I, George A. Terry, a citizen of the United States, residing at Buffalo, in the county of Erie and State of New York, have invented a new, original, and ornamental Design for a Drilling Attachment, of which the following is a specification, reference being had to the accompanying drawing, forming part thereof.

In the drawing:

Fig. 1 is an elevational view of a drilling at-

attachment showing my new design viewed from the front side thereof.

Figs. 2 and 3 are similar views from the right and left side, respectively, of the same.

Fig. 4 is a top plan view thereof.

Fig. 5 is a bottom plan view thereof.

I claim:

The ornamental design for a drilling attachment, as shown.

GEORGE A. TERRY.
